UNITED STATES PATENT OFFICE.

WILLIAM F. GRIMES, OF WASHINGTON, DISTRICT OF COLUMBIA.

INSULATOR.

Application filed February 8, 1922. Serial No. 535,029.

My invention relates generally to insulators, and more particularly to the suspension or strain type for high frequency circuits, such as radio antennæ, and has for an 5 object the provision of a device that will have both electrical and mechanical strength and which will reduce to a minimum the destructive effect of high frequency energy losses in the insulating material.

10 Another object of the invention is to provide a device in which damaged parts may be easily and quickly replaced by new ones without the necessity of disassembling the entire device.

15 A further object of the invention is the provision of a device so designed that should any insulated portion fail, the structure will not part but will retain its mechanical strength.

20 With these and other objects in view, the invention consists in the construction, combination and arrangement of parts as will be hereinafter described.

My insulator, as illustrated in the accompanying drawing, in which is shown the preferred embodiment of my invention, may be made entirely of insulating material, it being essential if a single material is used that it have both high compressional and high 30 tensile strength, or if two materials are used that one have high compressional strength and the other high tensile strength. Or any suitable high compressional strength insulating material and any suitable high tensile 35 strength metal may be used.

As illustrated, my invention consists of a number of sections A, B and C, it being understood that I do not desire to limit myself to the number of sections shown as it is necessary to use only sufficient sections to 40 distribute the electrical potential sufficiently to avoid tendency to corona effect.

The compressional strength insulating material is preferably made into tubular or rod-form members 5 having any desirable shape and which are seated in any convenient manner. I find a very stiff cement in caps 6 most effective. The caps are provided with flat extensions 7 adapted to be received in sockets 8 carried by channel bars 9.

50 The channel bars may be of any cross section and any desired material having high tensile strength, and the sockets 8 may form an integral part thereof or may be welded or otherwise securely fastened thereto with the end sockets parallel with and the center

sockets at right angles to the bars. The channel bars of each section are arranged in planes at right angles to each other, and the insulated members extend from the ends 60 of each of the bars to the center sockets of the opposite bars, thus avoiding a mass arrangement of the insulating material interposed between non-insulating parts. Such an open arrangement permits of having a 65 large part of the electric field in air reducing the losses in and destructive heating of the insulating material.

The tie rods 10 passing through the bars 9 hold the sections in spaced relation, the distance between the bars of adjacent sections being approximately twice that between the center sockets of each section. These tie rods may be of insulating or non-insulating material provided only that they have good 75 tensile strength.

In order that the best results may be obtained, sharp edges and corners should be avoided particularly at those points in the non-insulating material nearest points in 80 oppositely charged non-insulating material.

It is understood that the above description and accompanying drawing comprehend only the preferred embodiment of my invention, and that minor changes in details of proportion, combination and arrangement of parts may be resorted to without sacrificing 85 any of the advantages of my invention.

Having fully described my invention, what I desire to secure by Letters Patent 90 is:

1. In an insulator, the combination of spaced end bars at an angle to each other, means for attaching a wire to each extremity of each of the end bars, and at least four 95 insulating members one end of each of which is attached to the center of one of the end bars, the other end of each of which is attached to a point near the extremity of the other end bar, for rigidly holding the end 100 bars in spaced relation and angular orientation relative to each other.

2. A suspension insulator comprising a plurality of insulating sections, each section including end bars at an angle to each other, 105 sockets arranged at the ends and in the center of each bar, insulating members extending from the end sockets of each bar to the center sockets of the opposite bar, and tie rods for connecting said sections together.

WILLIAM F. GRIMES.
